A. C. HOPKINS

LIFTING JACK

Filed March 18, 1925

Patented Oct. 27, 1925.

1,559,099

UNITED STATES PATENT OFFICE.

ARTHUR C. HOPKINS, OF NILES, MICHIGAN, ASSIGNOR TO NATIONAL STANDARD COMPANY, OF NILES, MICHIGAN.

LIFTING JACK.

Application filed March 18, 1925. Serial No. 16,356.

To all whom it may concern:

Be it known that I, ARTHUR C. HOPKINS, a citizen of the United States, residing at Niles, county of Berrien, State of Michigan, have invented certain new and useful Improvements in Lifting Jacks, of which the following is a specification.

This invention relates to improvements in lifting jacks.

10 My present improvements relate to the type of lifting jack shown in my application for Letters Patent filed November 6, 1924, Serial No. 748,104, the same being in some respects an improvement over and an 15 adaptation of certain features of the structure of that application.

The main objects of this invention are:

First, to provide an improved lifting jack of the "dolly" type which may be very 20 easily manipulated to the position in which it is desired to use the same and may be moved about in relatively confined areas such as restricted spaces in garages, between automobiles, and the like.

25 Second, to provide an improved lifting jack which may be very quickly adjusted to and from the work and at the same time has a lifting means which is very powerful.

Third, to provide in a lifting jack an improved means for adjusting the lifting means to raise and lower the load.

30 Objects pertaining to details and economies of construction and operation of my improvements will definitely appear from 35 the detailed description to follow.

I accomplish the objects of my invention by the devices and means described in the following specification. The invention is clearly defined and pointed out in the 40 claims.

A structure embodying the features of my invention is clearly illustrated in the accompanying drawing forming a part of this application, in which:

45 Fig. I is a perspective view of a lifting jack embodying the features of my invention, the actuating lever being partially broken away.

Fig. II is a detail view mainly in central 50 longitudinal section on a line corresponding to line 2-2 of Figs. III and IV.

Fig. III is a transverse vertical section on a line corresponding to line 3-3 of Figs. I and II.

55 Fig. IV is a transverse vertical section

on a line corresponding to line 4-4 of Figs. I and II.

Fig. V is an enlarged detail section on a line corresponding to line 5-5 of Fig. III, showing details of the pawl control means. 60

In the drawing the sectional views are taken looking in the direction of the little arrows at the ends of the section lines and similar numerals of reference indicate similar parts in all of the views. 65

Referring to the drawing, the frame of the embodiment illustrated comprises a pair of side members 1 having laterally projecting arms 2 at the rear ends thereof to receive the spindles of the standards 3 of the 70 caster wheels 4. The frame members 1 are skeletonized for the sake of lightness.

The front yoke-shaped frame member 5 is secured to the front ends of the side members, the arms of the yoke being suitably 75 conformed to receive the side members. The front frame member 5 has a forwardly projecting arm 6 with a downwardly facing recess 7 therein adapted to receive the axle 8 of the front wheels 9. The axle is pivotally supported in this recess by means of the conical pivots 10 arranged through the front and rear walls of the recess so that the pivot axis of the axle is disposed longitudinally and centrally of the frame. The 80 wheels 9 are of such diameter that the frame may be swung to an upright position and moved about on the wheels; that is, the peripheries of the wheels project beyond the end of the frame. 90

The actuating lever 11 is pivotally mounted at the rear of the frame to constitute a tongue or steering means for manipulating the structure on its wheels, either when in horizontal or in upright position. I thus 95 secure a three-point support, the front wheels adjusting themselves to any uneven surfaces in the floor or ground thereby relieving the frame of undue strain and adding to the stability of the structure when 100 under load.

The lifting means comprises the lifting lever 12 which is pivoted at 13 and carries the lifting head 14, the head being pivotally mounted on the lever at 15. The lifting head or saddle is supported in its upright position by means of the link 16 which is pivoted to the head at 17 and to the frame at 18 thereby providing for a parallel movement of the link with the lifting lever and 110

supporting the head in its upright position.

At the rear of the lifting lever 11 journal a support 19 for the screw 20, the screw having a spherical head 21 engaging the 5 socket 22 in the lever below its pivot 13. The pivot constitutes the fulcrum for the lever and the screw the power means.

On this screw is a ratchet 23 having threaded engagement with the screw, the 10 ratchet being in the form of a disk having an annular series of holes 24 therein. The ratchet is also provided with a gear 25.

The lifting lever 11 is pivoted on the hangers 26 depending from the support 19, 15 the lever being mounted on the pivot 27 carried by these hangers. The lever is forked and has a pawl 28 mounted on each arm to coact with the ratchet on opposite sides of its axis so that the lifting lever 20 may be raised or lowered by throwing the proper pawl into operative relation to the ratchet. The means for accomplishing this consists of a control member 29 rotatably mounted on the lever pivot 27 and provided with opposed ears 30 through which the 25 retracting rods 31 are slidably arranged. These rods have pins 32 at their outer ends thus providing for a lost motion connection between the rods and the ears. The rods are pivoted at 33 to the pawls and have the springs 34 mounted thereon to be placed under compression when the 30 control member is adjusted to throw a pawl into operative relation.

35 The control member is manipulated by the adjusting rod 35 which is disposed longitudinally of the actuating lever.

To facilitate the rapid adjustment of the lifting means to and from the work I provide 40 a pinion 36 which is mounted on the shaft 37 carried by the upwardly projecting ears 38 on the support 19, the shaft having a hand wheel 39. By this means the lifting lever may be quickly raised or lowered to or from the work.

I have illustrated and described my improvements in an embodiment which I have found very practical. I have not attempted to illustrate or describe certain other embodiments or adaptations as I believe the disclosure made will enable those skilled in the art to embody or adapt my improvements as may be desired.

Having thus described my invention 55 what I claim as new and desire to secure by Letters Patent is:

1. In a lifting jack, the combination of a frame, a lifting lever pivotally mounted on said frame, a screw support pivotally mounted on said frame, an actuating screw mounted on said support to coact with said lifting lever, a ratchet driving member having threaded engagement with said screw, said driving member being provided with a gear, an actuating lever pivotally mount-

ed on said support, a pair of pawls mounted on said actuating lever to coact with said ratchet on opposite sides of its axis, a pawl control member rotatably mounted on the lever pivot and provided with oppositely disposed ears, pawl retracting rods having lost motion connections with said ears, pawl engaging springs arranged on said rods and adapted to be alternately placed under compression, a pinion mounted on said support to coact with said gear on said driving member and provided with a hand wheel to facilitate the rapid adjustment of the lifting lever to and from the work, and an adjusting rod for said control member disposed longitudinally of said actuating lever.

2. In a lifting jack, the combination of a frame, a lifting lever pivotally mounted on said frame, a screw support pivotally mounted on said frame, an actuating screw mounted on said support to coact with said lifting lever, a ratchet driving member having threaded engagement with said screw, said driving member being provided with a gear, an actuating lever pivotally mounted on said support, a pair of pawls mounted on said actuating lever to coact with said ratchet on opposite sides of its axis, a pawl control member rotatably mounted on the lever pivot and provided with oppositely disposed ears, pawl retracting rods having lost motion connections with said ears, pawl engaging springs arranged on said rods and adapted to be alternately placed under compression, and a pinion mounted on said support to coact with said gear on said driving member and provided with a hand wheel to facilitate the rapid adjustment of the lifting lever to and from the work.

3. In a lifting jack, the combination of a frame, a lifting lever pivotally mounted on said frame, a screw support pivotally mounted on said frame, an actuating screw mounted on said support to coact with said lifting lever, a ratchet driving member having threaded engagement with said screw, an actuating lever pivotally mounted on said support, a pair of pawls mounted on said actuating lever to coact with said ratchet on opposite sides of its axis, a pawl control member rotatably mounted on the lever pivot and provided with oppositely disposed ears, pawl retracting rods having lost motion connections with said ears, pawl engaging springs arranged on said rods and adapted to be alternately placed under compression, and an adjusting rod for said control member disposed longitudinally of said actuating lever.

4. In a lifting jack, the combination of a frame, a lifting lever pivotally mounted on said frame, a screw support pivotally mounted on said frame, an actuating screw mounted on said support to coact with said lifting

lever, a ratchet driving member having threaded engagement with said screw, an actuating lever pivotally mounted on said support, a pair of pawls mounted on said actuating lever to coact with said ratchet on opposite sides of its axis, a pawl control member rotatably mounted on the lever pivot and provided with oppositely disposed ears, pawl retracting rods having lost motion connections with said ears, and pawl engaging springs arranged on said rods and adapted to be alternately placed under compression.

5. In a lifting jack, the combination of a frame, a lifting lever pivotally mounted on said frame, a screw support pivotally mounted on said frame, an actuating screw mounted on said support to coact with said lifting lever, a ratchet driving member having 15 threaded engagement with said screw, said driving member being provided with a gear, an actuating lever pivotally mounted on said support, a pair of pawls mounted on said actuating lever to coact with said ratchet 20 on opposite sides of its axis, and a pinion mounted on said support to coact with said gear on said driving member and provided with a hand wheel to facilitate the rapid adjustment of the lifting lever to and from the 25 work.

6. In a lifting jack, the combination of a frame, a lifting member mounted on said frame, an actuating screw arranged to coact with said lifting member, a ratchet driving member having threaded engagement with said screw, said driving member being provided with a gear, an actuating lever, a pair of pawls mounted on said actuating lever to coact with said ratchet on opposite sides of 30 its axis, a rotatably mounted pawl control member provided with oppositely disposed ears, pawl retracting rods having lost motion connections with said ears, pawl engaging springs arranged on said rods to be alternately placed under compression by the 35 adjustment of said control member, and a pinion coacting with said gear on said driving member and provided with a hand wheel to facilitate the rapid adjustment of the lifting member to and from the work.

7. In a lifting jack, the combination of a frame, a lifting member mounted on said frame, an actuating screw arranged to coact with said lifting member, a ratchet driving member having threaded engagement with said screw, an actuating lever, a pair of pawls mounted on said actuating lever to coact with said ratchet on opposite sides of its axis, a rotatably mounted pawl control member provided with oppositely disposed ears, pawl retracting rods having lost motion connections with said ears, and pawl engaging springs arranged on said rods to be alternately placed under compression by the 60 adjustment of said control member.

8. In a lifting jack, the combination of a frame, a lifting member mounted on said frame, an actuating screw arranged to coact with said lifting member, a ratchet driving member having threaded engagement with said screw, said driving member being provided with a gear, an actuating lever, a pair of pawls mounted on said actuating lever to coact with said ratchet on opposite sides of its axis, means for selectively holding said pawls in inoperative positions, and a pinion coacting with said gear on said driving member and provided with a hand wheel to facilitate the rapid adjustment of the lifting member to and from the work.

9. In a lifting jack, the combination of a frame, a lifting member mounted on said frame, an actuating screw arranged to coact with said lifting member, a ratchet driving member having threaded engagement with said screw, a pair of pawls mounted on said actuating lever to coact with said ratchet on opposite sides of its axis, means for selectively holding said pawls in inoperative positions, and means independent of said actuating lever for rotating said driving member to facilitate the rapid adjustment of the lifting member to and from the work.

10. In a lifting jack, the combination of a frame comprising a pair of horizontally disposed spaced side members having laterally projecting arms at the rear ends thereof and a yoke-like front cross member having its arms secured to the front ends of said side members, said front frame member having a downwardly facing recess at its front end, caster wheels mounted on said arms, an axle disposed in said recess in said front frame member, pivots for said axle disposed on said front frame member centrally and longitudinally of the frame to support said axle in said recess, wheels on said axle, said wheels being of a diameter permitting the frame to be swung to an upright position on the axle, a lifting means carried by said frame, and an actuating lever for said lifting means mounted at the rear end of the frame to constitute a tongue therefor.

11. In a lifting jack, the combination of a frame comprising a pair of horizontally disposed spaced side members having laterally projecting arms at the rear ends thereof and a yoke-like front cross member having its arms secured to the front ends of said side members, said front frame member having a downwardly facing recess at its front end, caster wheels mounted on said arms, an axle disposed in said recess in said front frame member, pivots for said axle disposed on said front frame member centrally and longitudinally of the frame to support said axle in said recess, wheels on said axle, and a lifting means carried by said frame.

12. In a lifting jack, the combination of a frame comprising a pair of horizontally dis-

posed spaced side members and a yoke-like front cross member having its arms secured to the front ends of said side members, 5 caster wheels at the rear of said frame, an axle pivotally mounted in said front frame member with its pivot axis centrally and longitudinally of the frame, wheels on said axle, said wheels being of a diameter permitting the frame to be swung to an upright 10 position on the axle, a lifting means carried by said frame, and an actuating lever for said lifting means mounted at the rear end of the frame to constitute a tongue therefor with the frame in horizontal or in upright 15 position.

13. In a lifting jack, the combination of a

frame comprising a pair of horizontally disposed spaced side members and a yoke-like front cross member having its arms secured to the front ends of said side members, 20 caster wheels at the rear of said frame, an axle pivotally mounted on said front frame member with its pivot axis centrally and longitudinally of the frame, wheels on said axle, said wheels being of a diameter permitting the frame to be swung to an upright 25 position on the axle, and a lifting means carried by said frame.

In witness whereof I have hereunto set my hand.

ARTHUR C. HOPKINS.
